US00D777973S

(12) **United States Design Patent** (10) **Patent No.:** **US D777,973 S**
(45) **Date of Patent:** **** Jan. 31, 2017**

(54) **ORAL TOBACCO**

(71) Applicant: **British American Tobacco (Investments) Limited**, London (GB)

(72) Inventors: **Eva Sommarstrom**, London (GB); **David Rushforth**, London (GB)

(73) Assignee: **British American Tobacco (Investments) Limited**, London (GB)

(**) Term: **14 Years**

(21) Appl. No.: **29/522,016**

(22) Filed: **Mar. 26, 2015**

Related U.S. Application Data

(62) Division of application No. 29/434,323, filed on Oct. 11, 2012, now Pat. No. Des. 729,974.

(57) **CLAIM**

The ornamental design for oral tobacco, as shown and described.

DESCRIPTION

The patent or application file contains at least one drawing executed in color. Copies of this patent application publication with color drawing(s) will be provided by the Office upon request and payment of the necessary fee.

FIG. 1 is a right top perspective view of oral tobacco showing the design of an embodiment of the disclosed invention, and including color and surface texture;

FIG. 2 is a front perspective view thereof, the rear perspective view being substantially a mirror image thereof; and, FIG. 3 is a side perspective view thereof, the opposite side perspective view being substantially a mirror image thereof.

**1 Claim, 2 Drawing Sheets
(2 of 2 Drawing Sheet(s) Filed in Color)**
